DESIGN FOR A DRESS

Alan Eugene Phillips, New York, N. Y.

Application August 6, 1937, Serial No. 70,893

Term of patent 3½ years

To all whom it may concern:

Be it known that I, Alan Eugene Phillips, a citizen of the United States, residing at 118 W. 57th Street, in the Borough of Manhattan, city and State of New York, have invented a new, original, and ornamental Design for a Dress, of which the following is a specification, reference being had to the accompanying drawing, constituting a part thereof.

I claim:

The ornamental design for a dress, substantially as shown.

ALAN EUGENE PHILLIPS.
